UNITED STATES PATENT OFFICE.

FRANCIS X. MALOCSAY, OF NEW YORK, N. Y., ASSIGNOR TO INTERNATIONAL BANDING MACHINE COMPANY, OF NEW YORK, N. Y., A CORPORATION OF NEW YORK.

CIGAR-FEEDING DEVICE.

Application filed December 22, 1920. Serial No. 432,411.

To all whom it may concern:

Be it known that I, FRANCIS X. MALOCSAY, a citizen of the United States, and a resident of the city, county, and State of New York, have invented a certain new and useful Improvement in Cigar-Feeding Devices, of which the following is a specification.

This invention relates to a feeding device adapted to be used in connection with cigars and in which cigars may be rapidly fed in successive layers to a cigar banding machine or to a cigar bander and the object of this invention is to provide a feeding device of this character in which cigars which have been previously pressed into cigar boxes can be removed, banded and be placed into the box again with the bands on them, so that they assume the same position that they were in prior to being removed from the box.

A further object of this invention is to provide a cigar hopper in which layers of cigars are successively and quickly supplied to a cigar band applier should the work be done by hand or to an automatic cigar banding machine.

While the device is particularly applicable as a feeding device for cigars, it will be understood that when "cigars" are referred to, objects of any kind, particularly all objects of a cylindrical shape such as pencils, crayons or the like may be used.

With these objects, and other objects which may hereinafter appear in view, I have devised the particular arrangement of parts hereinafter set forth and more particularly pointed out in the claims appended hereto.

Reference is to be had to the accompanying drawings forming a part hereof in which—

Figure 1 is a side elevation of my improved cigar feeding device.

Figure 2 is a plan view of the same,

Figure 3 is an end view of the lower portion of the same,

Figure 4 is a longitudinal sectional view of the same on the line 4—4 of Figure 2 looking in the direction of the arrows, and

Figure 5 is another longitudinal sectional view of the device showing the same in its forward position and a layer of cigars that has been ejected from the hopper.

Throughout the various views of the drawings, similar reference characters designate similar parts.

In the preferred embodiment of my invention as disclosed in the accompanying drawings 1 indicates a support or table to which the device is adapted to be secured. At 2 is disclosed the bottom plate of the device which is secured upon the surface of the support by screws 3 or other fastening means. At 4 are the side plates of the hopper which are recessed as at 5. At the forward end of the device is an end strip 5^a, which, as the hopper is slid rearwardly, is adapted to abut against a stop 6 that limits the rearward movement of the hopper.

The stop 6 is in the nature of a transverse strip secured upon the bottom face 2 of the device.

At 7 is the rear end plate of the device which forms the end wall of the hopper. This end member terminates above the bottom member 2 leaving a space indicated at 8 for a purpose to be hereinafter set forth.

At 9 is a partition member which forms one of the walls of the hopper and is adapted to abut against the stop 6 as the hopper is slid forward. (See Figure 5). The hopper is slidable upon its bottom plate or member 2 and the bottom plate member 2 is provided at its side edges with longitudinally extending ribs 10 which project into complementary grooves 11 in the side members 4 of the hopper. The hopper, in which layers of cigars 12 are placed, is defined by the end plate 7 and the partition plate 9.

From the foregoing the operation of my improved device will be readily understood.

A number of layers of cigars are removed from a cigar box and placed in the hopper. This is usually done by means of a tape 88 which is wrapped about the cigars. After

the cigars have been deposited in the hopper as disclosed in Figures 2 and 4, the tape may be withdrawn through the recesses 5 in the side members 4. The hopper at this point is 100 in the position disclosed in Figures 1 and

5. To eject the lowermost layer of cigars from the hopper, the hopper is grasped by the handle 13 and withdrawn rearwardly, or in the direction of the arrow in Figure 1, 105 until the forward end strip 5^a contacts with the stop 6. When this position is reached, the lowermost layer of cigars has dropped

- down upon the surface of the support 1. The slideable hopper is then pushed forward to its former position (or the position shown in Figure 5) and it will be seen that a layer 5 of cigars remains deposited upon the surface of the support 1 as the cutaway portion 8 of the rear end strip 7 slides over the lowermost layer of the cigars and permits the same to remain on the table or support 1.
- 10 By rapidly moving the slideable hopper backward and forward successive bottom layers of cigars are removed as fast as they are needed for banding or for other purposes.
- 15 It will be seen that after a boxful of cigars is removed from their box or container and placed within the hopper 1 in the positions occupied by them when in the box, these cigars are ejected from the hopper in such a manner that after they are banded and are returned to the box from which they were taken, they will occupy their former places therein.
- 20 It will also be understood that while I have referred to my cigar feeding device as particularly adapted for feeding layers of cigars, it will be understood that with but a slight modification, the device can be arranged to feed single cigars or other articles.
- 25 30 From the foregoing, it is obvious that my invention is not to be restricted to the exact embodiment shown but is broad enough to

cover all structures coming within the scope of the annexed claims.

Having described my invention, what I claim is:

1. A device of the class described comprising a slideable hopper, a plate forming a bottom for said hopper, a support on which said plate is mounted, said hopper being movable on said plate and adapted to slide successive layers of cigars from the plate on to the support when said hopper is moved in one direction, said hopper being provided with a cut out portion in one of its walls whereby the hopper may slide over a layer of cigars deposited on the support without disturbing the same.
2. A device of the class described comprising a slideable hopper having side walls, said walls being recessed, a plate secured below said hopper forming a bottom therefor, a support on which said plate is fixed, said hopper being movable on said plate and adapted to slide successive layers of cigars from the plate on to the support when the hopper is moved in one direction, said hopper being provided with a cut out portion in one of its end walls whereby said hopper may slide over a layer of cigars deposited on the support on its movement thereover.

Signed at the city, county and State of New York this 8th day of December, 1920.

FRANCIS X. MALOCSAY.
